DESIGN.

G. W. REAM.
LANDSIDE FOR PLOWS.

No. 28,360.

Patented Mar. 8, 1898.

UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A LANDSIDE FOR PLOWS.

SPECIFICATION forming part of Design No. 28,360, dated March 8, 1898.

Application filed December 31, 1897. Serial No. 665,249. Term of patent 14 years.

To all whom it may concern:

Be it known that I, GEORGE W. REAM, a citizen of the United States, residing at Canton, in the county of Stark and State of Ohio, have invented and produced a new and original Design for Landsides for Plows, of which the following is a specification.

In the drawings, Figure 1 is a side elevation of a landside, showing my new design, this view being taken from the outside. Fig. 2 is an elevation taken from the inside. Fig. 3 is a plan view of Fig. 2. Fig. 4 is a rearview of the landside.

The leading feature of my design resides in the outline and in the surface configurations.

As shown in Fig. 2, a flange E projects from the bottom, beginning near the front, as shown at F, and extends entirely to the rear and then upwardly, following the configuration of the rearline D, being reduced in width near the top of the landside.

The upper edge of the inside of the landside is provided with flange G, which extends down to the bottom line, following the configuration of the front of the landside. This top flange is provided with an extension G', as shown in Figs. 2, 3, and 4.

The outside of the landside is substantially plain near its front end, but this becomes dished slightly near its lower edge and as it approaches the rear, as shown at I in Fig. 4.

What I claim is—

A design for the landside of a plow as herein shown and described.

In testimony whereof I affix my signature in presence of two witnesses.

GEORGE W. REAM.
